PRESSURE OPERATED SWITCH

Duncan B. Gardiner, Detroit, and Edmond A. Viale, Birmingham, Mich., assignors to Vickers Incorporated, Detroit, Mich., a corporation of Michigan

Application November 14, 1947, Serial No. 785,902

1 Claim. (Cl. 200—81.4)

1

The present invention relates to power transmissions of the hydraulic type, particularly to a pressure switch for use in power transmissions of this character. Power transmissions of this type are generally comprised of a pressure fluid source connected to one or more fluid motors for driving the same and directional control valves for controlling the flow of fluid to the motors. The directional control valves are frequently operated electrically as by solenoids. Where the transmission installation requires that the solenoids be operated in response to pressure changes in the system, pressure switches are employed.

The number of different possible hydraulic circuits in which a pressure switch may be used is almost countless, each circuit requiring slightly different pressure responses of the pressure switch for satisfactory operation. In addition, the circuits vary as to differential between cut-in and cut-out pressure.

In the past, it was necessary to use different types of pressure switches to meet various pressure operating requirements. Although some switches were of the adjustable type, the cut-in and cut-out pressure response points could not be individually selected.

It is an object of this invention to provide a pressure switch system in which both the cut-in and cut-out points may be independently selected, and which may be adjusted to provide any differential desired.

It is a further object of this invention to provide an improved pressure responsive switch which is adapted for installation in circuits having widely different pressure characteristics.

It is also an object of this invention to provide a pressure switch of this character of simple and reliable construction which is inexpensive to manufacture and which is readily adaptable to various installation requirements by a simple adjustment.

Further objects and advantages of the present invention will be apparent from the following description, reference being had to the accompanying drawing wherein a preferred form of the present invention is clearly shown.

In the drawing:

Figure 1 is a sectional view of a preferred form of the present invention taken on line 1—1 of Figure 2.

Figure 2 is a sectional view taken on line 2—2 of Figure 1.

Figure 3 is a diagrammatic view embodying a preferred form of the present invention.

Referring now to Figure 1, there is shown a

2

pressure switch 10 comprised of a U-shaped housing 12 provided with a pressure supply port 14 and a drain port 16.

The pressure supply port 14 is connected by a passage 18 to a pair of vertical bores 20 and 22 within which pistons 24 and 26 are respectively mounted. The bores 20 and 22 are closed at their lower ends by plugs 28 and 30.

Referring now to Figures 1 and 2, the pistons 24 and 26 are limited in their vertical movement by duplicate pins 32 which are stationarily mounted by means of mounting screws 34 in duplicate bores 36 which respectively intersect the bores 20 and 22. The pistons 24 and 26 are provided with transverse bores 38 and 40, respectively, through which the pins 32 are inserted. The diameters of the pins 32 and of the transverse bores 38 and 40 may be carefully selected to determine the total reciprocal movement of the pistons 24 and 26. The pistons 24 and 26 are biased to the position shown by means of springs 42 and 44 of predetermined resistance which are mounted in upper and lower spring retainers 46 and 48. The lower spring retainers 48 abut 20 duplicate piston retainers 50, the function of which is to operate a pair of plunger pins 52 and 54 mounted in vertical bores 56 and 58 which are located on different planes. The resistance of the springs 42 and 44 may be independently 25 adjusted by means of adjusting screws 60 and 62 for selectively varying the cut-in and cut-out pressures of the switching system.

At the bottom of the housing 12, a pair of switches 64 and 66 are connected to a bracket 68 by means of through bolts 70. The bracket 68 is fastened to the bottom of the housing 12 by means of mounting screws 72. The switches may 35 preferably be of the single-pole single throw plunger type which are well known in the prior art. Preferably two duplicate switches of the normally closed type are used in the invention which are maintained in the open position as follows: The switches 64 and 66 are provided with plungers 74 and 76 which are biased downwardly by the plunger pins 52 and 54 so as to normally maintain the switches in the open position shown. Thus, when the pistons 24 and 26 are actuated upwardly, the plungers snap upwardly to close the switches.

50 The body 12 and the switches are protectively closed by cover 78. It should be noted that all of the pressure actuated mechanism is mounted in one side of the U-shaped body and that the pressure fluid supply to the pistons is delivered through a single conduit 18 which intersects

both bores 20 and 22 within which the pistons 24 and 26 are mounted. The cavity formed between the two sides of the U-shaped housing provides a convenient mounting location for the springs 42 and 44. The arrangement is such that the switches may be conveniently fastened to the same side of the housing in which the pressure actuating mechanism is mounted. The U-shaped housing not only provides a cavity for convenient mounting of the springs 42 and 44 but also permits the springs to perform the dual function of biasing both the fluid operated pistons and the plunger pins which actuate the switches to one of their positions of operation. The opposite side of the housing provides abutment means for the springs so that the two springs are only opposed by the pressure biased pistons, thus obviating linkage which would tend to introduce friction. The opposite side of the housing not only provides an abutment for the springs but provides mounting structure for the adjusting screws 60 and 62 which are placed closely together to facilitate adjustments of the switching mechanism.

Referring now to Figure 3, for the purpose of illustrating the operation of the switching system, there is shown a solenoid operated control valve indicated by the numeral 80. The control valve 80 is adapted to be operated by right and left end solenoids indicated respectively by the numerals 82 and 84. One terminal of the solenoid 82 is adapted to be connected to a line 86 by lines 88 and 90. The other terminal of the solenoid 82 is adapted to be connected by a line 92 to the first of a pair of contacts 94 and 96 of a holding relay 98 which is also provided with two other pairs of contacts 100 and 102 and 104 and 106. The line 86 is connected to one end of the relay 98. The coil of the relay 98, indicated by the numeral 108, operates a plunger core 110 with which is associated an arm 112 for controlling the contacts 94 and 96, an arm 114 for controlling the contacts 100 and 102, and an arm 116 for controlling the contacts 104 and 106. The relay 98 when de-energized is in the position shown and when energized, closes the contacts 104 and 106 and 100 and 102, and breaks the contacts 94 and 96.

One terminal of the solenoid 84 is also connected to the line 88 while the other terminal thereof is connected by a line 118 to the contact 100 of the relay 98.

Referring now to the switches 64 and 66, the former is provided with a lever arm 120 and the latter with a lever arm 122. The lever arms 120 and 122 are adapted to be maintained in the position shown by the plunger pins 54 and 52, respectively, the latter of which respectively engage the plungers 76 and 74 of the switches 64 and 66.

In the position shown, the lever arm 120 breaks the connection between a line 124 and a line 126 while the lever arm 122 breaks the connection between a line 128 and a line 130. Both of the lines 124 and 128 are connected to a line 132 which is connected at one extreme end to the contact 102 of the relay 98. The opposite end of the line 132 together with that of line 86 is adapted to be connected in the well known manner to an electrical supply source. The lines 126 and 130, which are respectively connected to the switches 64 and 66 are connected at their opposite ends to the contacts 104 and 106 of the relay 98. A line 134 connects the line 132 to the other end of the relay 98 for

the purpose of energizing the same and a line 136 connects the line 132 to the contact 96 of the relay 98.

Referring now to Figures 1, 2, and 3, in operation, and presuming for the purpose of illustration that switch 64 will be operated at 500 lbs. per square inch and that switch 66 will be operated at 1000 lbs. per square inch, with the pressure of the system below 500 lbs. per square inch, solenoid 82 of the control valve 80 is energized, and solenoid 84 and relay 98 are de-energized. Solenoid 82 is energized by means of a circuit being formed by lines 86, 88, and 90, the terminals of the solenoid 82, line 92, contacts 94 and 96 of relay 98, and the lines 136 and 132. When the pressure reaches 500 lbs. per square inch, the plunger 26 is lifted, and the bias force retaining plunger pin 54 on the plunger 76 of switch 64 is removed so as to operate lever arm 120 to the closed position. The operation of switch 64 to the closed position does not change the circuit which energizes solenoid 82 and de-energizes the solenoid 84 and relay 98. The operation of the switch 64 merely readies the system for a holding circuit to be later established and hereinafter described. When the pressure reaches 1000 lbs. per square inch, the piston 24 is lifted against the resistance of spring 42. With the bias force on plunger pin 52 removed, plunger 74 of the switch 66 operates the lever arm 122 of the switch 66 also to the closed position so as to connect line 128 to line 130. A circuit is immediately established for energizing the relay 98 by the lines 132 and 128, switch 66, lines 130 and 134, coil 108 and line 86. When the relay 98 is energized, the arms 112, 114, and 116 are lifted so as to break the contacts 94 and 96 and to close the contacts 102 and 100 and 104 and 106. With contacts 94 and 96 broken, the circuit energizing solenoid 82 is broken and the solenoid becomes de-energized. The solenoid 84 is energized by the closure of contacts 100 and 102, the following circuit being established: Lines 86 and 88, the terminals of the solenoid 84, line 118, contacts 100 and 102 of the relay 98, and line 132. Simultaneously, with the opening of the other relay contacts, closure of contacts 104 and 106 completes the relay holding circuit which holds the relay energized through the following path; one end of the relay coil 108 is connected to line 86 and the other end of the relay coil is now connected to line 132 through lines 134 and 130, operated contacts 106 and 104, line 126, switch 64, and line 124. When the pressure falls below 1000 lbs. per square inch, the lever arm 122 of the switch 66 is operated by means of the spring 44 forcing the retainers 48 and 50 to shift the plunger pin 52 downwardly so as to operate the plunger 74. With the switch 66 in the open position, the relay is maintained in the energized position by means of the holding circuit previously established. Solenoid 84 continues to be energized and solenoid 82 continues to be de-energized. When the pressure falls below 500 lbs. per square inch, the spring 44 forces the retainers 48 and 50 downwardly against the plunger pin 54 which shifts the plunger 76 of the switch 64 to operate the lever arm 120 of the switch 64 to the open position. This opens the holding circuit thereby de-energizing the relay 98. When the relay coil 98 is de-energized, solenoid 84 becomes de-energized while solenoid 82 becomes energized.

The cut-in and cut-out pressures of the switching unit 10 may be easily selectively determined

by adjustment of the screws 60 and 62. Thus, both the cut-in and cut-out pressures may be raised or lowered, and in addition, either the cut-in or cut-out pressure may be raised or lowered, independently of the other.

While the form of embodiment of the invention as herein disclosed constitutes a preferred form, it is to be understood that other forms might be adopted, all coming within the scope of the claim which follows.

What is claimed is as follows:

A pressure responsive switching mechanism comprising a substantially U-shaped housing having two sides with a cavity formed therebetween, a pair of hydraulically operated pistons shiftably mounted in the first side of the housing, separate resilient means mounted in the cavity and biasing each piston to one position of operation, means forming a single, common fluid pressure supply conduit in the first side of the housing and connected to the pistons, said pistons being responsive to predetermined increases of pressure for shifting to a second position and overcoming the resilient biasing means, a pair of switches fastened to the first side of the housing, said switches being of the open and close type and biased to one position of

operation, separate means shiftably mounted in the first side of the housing operatively connected to the switches and separately biased by the resilient biasing means to normally operate the switches to their second position of operation, and separate adjusting means for each resilient biasing means mounted in the second side of the housing for independently determining the pressures at which each switch is operated to the first position of operation.
